UNITED STATES PATENT OFFICE.

JERROLD F. WALTON, OF STURGIS, MICHIGAN.

DESIGN FOR A CHAIR-BACK.

45,663.

Specification for Design.

Patented Apr. 21, 1914.

Application filed February 11, 1914. Serial No. 818,166. Term of patent 14 years.

To all whom it may concern:

Be it known that I, JERROLD F. WALTON, a citizen of the United States, and a resident of Sturgis, county of St. Joseph, State of Michigan, (whose post-office address is Sturgis, Michigan,) have invented a new, original, and ornamental Design for a Chair-Back, of which the following is a specification, reference being had to the accompanying drawing, forming a part thereof.

The figure is a perspective view of a chair back, showing my new design.

I claim:

The ornamental design for a chair back, as shown.

JERROLD F. WALTON.
